MAGNETIC CODING APPARATUS

Joseph John Saykay, Sea Cliff, N.Y., assignor to Fairchild Camera and Instrument Corporation, a corporation of Delaware

Filed Apr. 2, 1963, Ser. No. 270,055
6 Claims. (Cl. 340—147)

This invention relates in general to coding apparatus. While it is of general utility and has general application it is particularly suitable for use with a key operated machine such as a typewriter to provide a code representation of information selected at the keyboard in a form suitable for storage, transmission or the like. In the description, the invention will be described as it might be used in such an application.

The prior art has taught that coding devices of various types may be used with an ordinary typewriter to provide a punched tape or other output suitably coded to be used to operate automatic devices such as an automatic typesetting machine. One form of coding device suitable for such use is described and claimed in United States Patent 3,065,298 assigned to Fairchild Camera and Instrument Corporation, the assignee of the instant invention.

The novel coding device described in that patent permits not only alpha-numeric information but also information as to type widths in various increments to be translated into coded punched tape by means of a code matrix using a minimum number of diodes. This results in a saving in cost as well as mitigating the problem of reverse leakage current encountered in such apparatus when a large number of diodes are connected in parallel. Alternatively, coding devices could be used with a machine such as a tape perforator, etc., providing pattern of signals in a predetermined code which, in turn, may be used to control a typewriter.

While the subject matter of United States Patent 3,065,298 has proven acceptable in actual usage, certain problems still remain in some applications despite the many advantages it provides. For example, each selected diode in the matrix carries full load current which, under certain conditions could cause arcing at the switch contacts; leakage or reverse current through non-selected diodes, though substantially reduced, is still present; 64 double switches, one for each of the 64 valid combinations possible, are required which, in addition to the cost consideration, increases the "touch" or force required to be exerted at the keyboard.

Accordingly, it is an object of the invention to provide a new and improved coding apparatus.

It is another object of the invention to provide a new and improved coding apparatus in which the disadvantages of the prior art are avoided.

Briefly stated, in accordance with the invention a coding apparatus comprises a plurality of banks of units, all but one unit in each bank including at least one contact pair having a normal condition and also actuating means responsive to the passage of current therethrough to temporarily change the normal condition of the contact pairs in its unit. The remaining unit in each bank is an impedance. Means are further provided for establishing a circuit including one of the actuating means or the impedance from each bank. A corresponding contact of all the contact pairs is connected to one of a plurality of output lines associated with each bank in accordance with a predetermined code; the other contact of all the contact pairs is adapted to be connected to a source of potential.

For a better understanding of the present invention, together with other and further objects thereof, reference is had to the following description taken in connection

2

with the accompanying drawing, while its scope will be pointed out with particularity in the appended claims.

In the drawing:

FIGURE 1 is a schematic representation of a coding apparatus embodying the invention;

FIGURE 2 is a schematic representation of a modification of the apparatus shown in FIGURE 1.

Referring now to FIG. 1 the coding apparatus shown therein includes two banks 11 and 12 of units respectively controlling output lines 13—15 and 16—18. There are eight input conductors 19—26 and 27—34 associated respectively with banks 11 and 12. All but one unit in each bank includes a switch actuating element shown in the embodiment as magnetic field-producing coils or electromagnetic relays 35a—48a, one associated with each of conductors 19—34, and one or more single-pole switches or contact pairs 35b—48b associated with each coil. Coils 35a—41a associated with lines 19—26 have one end connected to a source of potential 49 which may be of any polarity relative to a reference potential and which is shown here as the positive side of a battery the other side of which is connected to a point of reference potential or ground. Coils 42a—48a associated with conductors 27—34 have one end connected to the point of reference potential as indicated at numeral 50.

In addition to units 35a—35b, 36a—36b . . . 48a—48b, a dummy unit is provided in each of banks 11 and 12 identified as elements 51 and 52 and respectively, each connected in a manner identical to the coils in their associated banks. Dummy units 51 and 52 are used to enable the production of those output patterns which require the absence of a signal at any of the output conductors associated with one or both of banks 11 and 12. Preferably, each of dummy units 51 and 52 is a resistor having a value equal to the resistance of one of coils 35a—48a. Alternatively, any desired dummy unit may be a unit identical to any of units 35a—35b, 36a—36b . . . 48a—48b. In such case the contact pairs of the units used in place of dummy units 51 and 52 would not be connected to any output line.

A plurality of other single-pole switches are provided of which two are identified by numerals 53 and 54. In a typical embodiment such as that discussed in the introduction, the eight input conductors in each of banks 11 and 12 enable the selection of sixty-four different combinations of two conductors, one from each bank. Sixty-four single-pole switches may then be used as illustrated, each of the type identified by numerals 53 and 54, and each connecting a different pair of conductors, one from the group containing conductors 19—26, the other from the group containing conductors 27—34. When any one of the sixty-four switches is closed, as for example, by selection of a key on a typewriter keyboard, a circuit is established which includes a unique pair of actuating coils, one from bank 11 and the other from bank 12. For example, when switch 54 is closed a path is provided from potential source 49 through coil 35a, conductor 20, switch 54, conductor 34 and coil 48a to the reference potential point 50. The potential impressed across the pair of elements thus selected, one of coils 35a—41a or dummy unit 51, and one of coils 42a—48a or dummy unit 52, results in a current flow through the circuit and the provision of a magnetic field by each coil included in the pair of elements selected.

The coding apparatus illustrated has six output conductors 13—18 which might, for example, be connected to the actuators of six punches or to any other desired load. Output conductors 13—15 are associated with the switches or contact pairs included in bank 11 and output conductors 16—18 are associated with the switches or contact pairs included in bank 12. In this embodiment each

of switches 35b-48b includes at least one and as many as three contact pairs which may be of the so-called "reed" or "glass reed" variety. In the embodiment illustrated each of these switches includes a pair of contacts, the contacts of switch 43b being identified by reference numerals 55 and 56. Of course, here need be no switches associated with dummy units 51 and 52.

The contact of each of switches 35b-48b corresponding to contact 55 of switch 43b is connected to a source of potential 57 which may have a value the same as or different than that of source 49 depending upon the particular application of the apparatus. In this embodiment source 57 is also shown as the positive terminal of a battery the other terminal of which is returned to a source of reference potential or ground.

The other contact of each of switches 35b-41b is connected to one of output conductors 13-15 and the other contact of each of switches 42b-48b is connected to one of output conductors 16-18 all in accordance with a predetermined code. It will be noted that where more than one contact pair or switch is associated with a single coil, e.g. coil 41a which has three contact pairs or switches 35b associated therewith, each of the switches so associated is connected to a separate output line, in accordance with the predetermined code.

In the embodiment shown, passage of current through any selected pair of elements (coils 35a-48a and dummy units 51 and 52) by actuation of selected key-actuated switches 53, 54, etc., will close the contacts of all the switches associated with any selected coil. It is clear, of course, that the coding apparatus could operate equally well were it arranged so that switches 35b-48b were normally closed and were selectively opened by passage of current through associated coils and similarly the switches typified by switches 53 and 54 could be normally closed and selectively opened.

To make the output pattern provided by the several coils clear, the following table is presented summarizing the results observable on output conductors 13-15 when current flows through any one of coils 35a-41a or dummy unit 51. Of course, in the embodiment shown current can only pass through a pair of coils, one from bank 11 and one from bank 12, but the identical pattern is observable on output conductors 16-18 when any one of coils 42a-48a or dummy unit 52 has current pass therethrough and consequently the abbreviated table is sufficient. In the table, the symbol "0" is used to indicate the normal signal condition of the output conductor, in this embodiment when all switches connected to that line are open, and the symbol "1" is used to indicate the change in signal condition of the output conductor when a switch connecting potential source 57 thereto is closed.

OUTPUT CONDUCTORS

	15	14	13
Dummy 51	0	0	0
Coil 35a	0	0	1
Coil 36a	0	1	0
Coil 37a	0	1	1
Coil 38a	1	0	0
Coil 39a	1	0	1
Coil 40a	1	1	0
Coil 41a	1	1	1

It should now be clear that by selecting one of coils 35a-41a or dummy 51 from bank 11 and one of coils 42a-48a or dummy 52 from bank 12 any one of 2⁶ or 64 distinct and unique patterns of signals may be provided on the 6 output lines 13-18. In addition, the apparatus for doing this, the circuit shown in FIG. 1 accomplishes this with only 64 single switches (to connect one of lines 19-26 with one of lines 27-34) and only 14 reed switch units 35a-35b, 36a-36b etc. It should also be noted that the selection is made through control circuitry which is not physically connected to the matrix and output lines. This disjunction, in addition to other advantages, permits virtually complete freedom in selecting optimum voltage and current output levels for any particular application, which levels may be different from the level of the control signals applied to the glass reed switch actuating elements, i.e. coils 35a-48a.

The circuit shown in FIG. 1 could be expanded to permit combinations in excess of 64 by increasing the number of banks of units, in a manner similar to that discussed in Patent 3,065,298. Of course, were expansion accomplished in that manner then switches 53, 54 etc. would have to be of the multiple contact type.

A preferred method of increasing the number of available code combinations is to increase the number of units in each bank, at the same time increasing the maximum number of single-pole switches or contact pairs that a given unit must handle.

For a two bank apparatus the relationship between input conductors, output conductors, bank units, the maximum number single-pole switches or contact pairs any unit must have, and the number of available code combinations is as follows:

35 $w =$ number of output conductors in first bank.
 $x =$ number of output conductors in second bank.
 $w =$ maximum number of single-pole switches or contact pairs any unit in first bank must have.

40 $x =$ maximum number of single-pole switches or contact pairs any unit in second bank must have.

$y =$ number of input conductors in first bank.

$z =$ number of input conductors in second bank.

$yz =$ number of code combinations available.

$(yz-1 =$ number of usable code combinations.)

45 $y-1 =$ number of units in one bank plus one dummy unit.
 $z-1 =$ number of units in second bank plus one dummy unit.

50 The relationships then are as follows:

The number of code combination representable is equal to the product of the number of input conductors in each bank, or to the value of 2 raised to a power equal to the total number of output conductors. That is, the maximum number of possible code combinations using a straight binary code is equal to yz or 2^w+x whichever is less.

In a symmetrical arrangement, $w=x$, $y=z$, and $yz=2^{w+x}$ or $y^2=2^n$ where $n=2w=2x$. In this case no unit in a bank would have to include more than $n/2$ single-pole switches or contact pairs.

The following table shows a typical sequence of expansions, the last example permitting 4,096 separate code combinations to be represented:

Number of Output Conductors and/or Maximum Number of Switches Any Unit Must Have in Each Bank	Number of Input Conductors Each Bank	Maximum Code No.	Total Number Units in Each Bank Excluding Two Dummies
3:3	8:8	64	14
4:3	16:8	128	22
4:4	16:16	256	30
5:4	32:16	512	46
5:5	32:32	1024	62
6:5	64:32	2048	94
6:6	64:64	4096	126
W:X	Y:Z	2 ^{w+x} or WX	Y+Z-2

In FIG. 2 structure which is the same as structure in FIG. 1 has the same reference numeral as its counterpart, differing by 100. This figure has been simplified by omitting, for example, all but two switches 153 and 154. Thus bank 11 of FIG. 1 corresponds to bank 111 of FIG. 2 and coil 35a of FIG. 1 corresponds to coil 135a of FIG. 2. Basically, the theory behind, and the operation of this construction is the same as that illustrated in FIG. 1.

The primary difference between the embodiment of FIG. 1 and that of FIG. 2 is that both elements comprising each switch unit, actuating means or coil and contact pair, is connected at one end to the same source of potential. Thus, one end of each of coils 135a-141a in bank 111 is connected to potential source 200 shown as the positive terminal of a battery, the other terminal of which is connected to a source of reference potential or ground. One of each of the contact pairs constituting the switches 135b-141b associated with coils 135a-141a is also connected to potential source 200. Similarly, one end of coils 142a-148a in bank 112 is connected to potential source 201 which has a value different than the value of potential source 200, shown here as the negative terminal of a battery, the other terminal of which is connected to a source of reference potential. Here again, one of each of the contact pairs in this bank is connected to potential source 201, the other one of each of the contact pairs being connected to one of output lines 113-118 as was the case with the embodiment shown in FIG. 1.

The tables set forth above are valid for the embodiment of FIG. 2. It will be appreciated that in this embodiment too, there is no problem of reverse current flow, etc.

While there has been described what is at present considered to be the preferred embodiment of the invention, it will be obvious to those skilled in the art that various changes and modifications may be made therein without departing from the invention, and it is, therefore, aimed in the appended claims to cover all such changes and modifications as fall within the true spirit and scope of this invention.

What is claimed is:

1. A coding apparatus comprising a plurality of banks of units, all but one of said units in each of said banks including at least one contact pair having a normal condition and actuating means responsive to the passage of current therethrough for temporarily changing the normal condition of the contact pairs included in that unit, the other unit in each of said banks comprising an impedance, a current-supply circuit for said actuating means, means for establishing a circuit including said current-supply circuit and any chosen pair of said actuating means and said impedances, each from a different one of said banks, a plurality of output conductors associated with each of said banks, a corresponding contact of all of said contact pairs being connected to said output conductors associated with their respective banks in accordance with a predetermined code, current-supply circuit for said output conductors, the other contact of all of said contact pairs being connected to said current-supply circuit for said output conductors.

2. A coding apparatus comprising at least a first and second bank of units, said first bank having w units, said second bank having x units, all but one of said units in each bank including an electromagnetic relay having at least one contact pair associated therewith, said other unit in each of said banks comprising an impedance, a first current supply circuit, wx switches each operable to establish a circuit including said first current supply circuit and any chosen one of said electromagnetic relays or said impedance from each of said banks of units, y output conductors associated with said first bank of units, z output conductors associated with said second bank of units where $2^{y+z} = wx$, a second current supply circuit, a corre-

sponding contact of all of said contact pairs being connected to said output conductors associated with their respective banks in accordance with a predetermined code, the other contact of all of said contact pairs being connected to said second current supply circuit.

3. A coding apparatus comprising at least a first and a second bank, said first bank having $w-1$ electromagnetic relays, said second bank having $x-1$ electromagnetic relays, an impedance in each of said banks, a first current-supply circuit, wx switches each operable to establish a circuit including said first current-supply circuit and any chosen one of said electromagnetic relays or said impedance from each of said banks of units, y output conductors associated with said first bank of units, z output conductors associated with said second bank of units where $2^{y+z} = wx$, at least one and as many as y contact pairs operable by each relay in said first bank, at least one and as many as z contact pairs associated with and operable by each relay in said second bank, a second current supply circuit, a corresponding contact of all of said contact pairs being connected to said output conductors associated with their respective banks in accordance with a predetermined code, the other contact of all of said contact pairs being connected to said second current supply circuit.
4. A coding apparatus comprising at least a first and a second bank, said first bank having $w-1$ electromagnetic relays, said second bank having $x-1$ electromagnetic relays, an impedance in each of said banks, a plurality of current-supply circuits, wx switches each operable to establish a circuit including first and second ones of said current supply-circuits and a chosen one of said electromagnetic relays or said impedance from each of said banks of units, y output conductors associated with said first bank of units, z output conductors associated with said second bank of units where $2^{y+z} = wx$, at least one and as many as y contact pairs associated with and operable by each relay in said first bank, at least one and as many as z contact pairs associated with and operable by each relay in said second bank, a corresponding contact of all of said contact pairs being connected to said output conductors associated with their respective banks in accordance with a predetermined code, the other contact of all of said contact pairs in each of said banks being connected to third and fourth ones of said supply circuits respectively.
5. A coding apparatus comprising at least a first and a second bank, said first bank having $w-1$ electromagnetic relays, said second bank having $x-1$ electromagnetic relays, an impedance in each of said banks, a first and second current-supply circuits, wx switches each operable to establish a circuit including first and second ones of said current-supply circuits and a chosen one of said electromagnetic relays or said impedance from each of said banks of units, y output conductors associated with said first bank of units, z output conductors associated with said second bank of units where $2^{y+z} = wx$, at least one and as many as y contact pairs associated with and operable by each relay in said first bank, at least one and as many as z contact pairs associated with and operable by each relay in said second bank, a corresponding contact of all of said contact pairs being connected to said output conductors associated with their respective banks in accordance with a predetermined code, the other contact of all of said contact pairs in each of said banks being connected to said first and second supply circuits respectively.
6. A coding apparatus comprising at least a first and a second bank, said first bank having $w-1$ electromagnetic relays, said second bank having $x-1$ electromagnetic relays, an impedance in each of said banks, a first current-supply circuit, wx switches each operable to establish a circuit including said first current-supply circuit, a chosen one of said electromagnetic relays or said impedance from each of said banks of units, and ground, y output conductors associated with said first bank of units, z output

conductors associated with said second bank of units where $2y+z=wx$, at least one and as many as y contact pairs associated with and operable by each relay in said first bank, at least one and as many as z contact pairs associated with and operable by each relay in said second bank, a second current supply circuit, a corresponding contact of all of said contact pairs being connected to said output conductors associated with their respective banks

in accordance with a predetermined code, the other contact of all of said contact pairs being connected to a second one of said current-supply circuits.
